(57) **CLAIM**

The ornamental design for an electronic musical instrument control ring, as shown and described.

DESCRIPTION

FIG. 1 is a top view of an electronic musical instrument control ring showing our new design; and, FIG. 2 is a front elevation view thereof.

The broken lines showing portions of the electronic musical instrument control ring are included for the purpose of illustrating portions of the article and form no part of the claimed design.

1 Claim, 2 Drawing Sheets
